CLEANER'S GARMENT SIZING FORM

Wallmuth R. Frentzel, Chehalis, Wash.

Application April 3, 1937, Serial No. 134,829

7 Claims. (Cl. 223—70)

The cleaning of dresses, skirts, jackets or other garments of certain shrinkable or fragile materials, especially those of knit materials, and of certain types of crepe materials, produces a great deal of controversy between the cleaner and his customers, by reason of the fact that such materials tend to shrink, and must be resized or stretched by the cleaner. The shrinking is a natural and unavoidable result of treatment of the garment during the cleaning process, accompanied sometimes and aggravated by the removal of sizing material during the cleaning, and as a necessary result thereof. The cleaner, forced to the necessity of stretching the garment, sometimes injures the fabric thereof permanently, this occurring in large measure because the stretching is done only between selected points, laterally and longitudinally, and not throughout any considerable area, nor radially and uniformly throughout. Some materials tend to stretch or bag in spots when cleaned, and these must be shrunk in drying, uniformly and carefully, to bring them back to proper size. Pile fabrics, as velvet, must be dried and sized in such manner that the pile is not flattened, but stands up uniformly all over. Furthermore, the cleaner must rely on flat measurement of the garment, taken before cleaning, to which measurement it is stretched after cleaning, while lying flat upon a table, or while mounted upon flat forms which may be expanded in various ways. While there are forms of generally human shape whereon a garment may be placed while it is drying or being otherwise operated upon in the cleaning process, many such forms come in various fixed sizes, and those which are adjustable are not adjustable in different amounts in different directions at different points, nor so adjustable differentially and simultaneously, nor so adjustable in selected and variable zones vertically. Some forms of the flat type have been proposed, which have limited capability for adjustment, but these are not suitable to the proper drying of the garment after cleaning, or to the application of a sizing material, if required. Cleaners heretofore have had to rely upon a fiction designated as the average human figure, and have attempted to size and conform garments to an average figure of a given size. Actually there is no average human figure. Each figure is individually different from other figures. It cannot be said that a figure having a bust measurement of 36 will necessarily have a waist measurement of 30, or a hip measurement of 42. Such individual measurements in circumferential zones about the figure vary with different individuals.

Nor can it be said that there is an average figure insofar as length goes, and the spacing of these measurement zones, nor that there is any relationship between the circumferential measurement at such zones and the height of the figure or the spacing of such zones. A woman may be 5 feet 3 inches tall, and yet have a bust measurement of 38, or may be short waisted, so that the zone of bust measurement is extremely close to the zone of waist measurement. A woman may be 5 feet 10 inches tall, and yet have a bust measurement of 33, and this tall woman may be extraordinarily short waisted.

As a result of these variations of individual figures the best the cleaner can do, with the methods and forms heretofore available, is to try to restore the garment by lateral and longitudinal stretching, by hand, to a chart or to measurements in the flat that correspond to the original flat measurements, or to put it upon a figure which is not 20 adjustable, but which is sized to accommodate the so-called average figure, and which in particular is not adjustable lengthwise of the figure to accommodate variations in the spacing of the several zones of measurement. He is helpless when he must shrink a garment, especially in a local area. The result may be, and frequently is, a garment which does not fit as originally to the wearer, which may be bulged too much at one point and stretched too little at another point, 30 which may have an uneven hem, and which, to a critical customer, is far from satisfactory.

It is a primary object of this invention to provide a form for the use of cleaners in sizing garments which may be adjusted individually at the several critical zones of measurement, that is to say, in a circumferential direction, and which may be adjusted vertically to vary the spacing of these zones of measurement, and in which, in addition, the expansion in the different zones is so controlled as to expand the garment in the part of that zone which requires expansion to fit a particular figure, and which is expanded less in that zone to fit other parts of the figure, but which, over the whole area of the garment, stretches all 40 parts substantially uniformly, without undue concentration of the stretching force at any one point.

In such forms as are adjustable, usually of the flat type, the adjustment accomplishes 50 stretching only by pulling the garment laterally, that is, from one side seam to another, and this will not provide adequate fullness over the hips for many figures, and in attempting to adjust the garment to the wearer it will be found that it 55

hangs crookedly because all the stretching has been in a lateral direction. It is therefore an object of this invention to devise a form for such use which will provide substantially radial stretching at all points, and in such proportion as to make the garment hang straight upon the wearer.

In the flat forms referred to, some of which are adjustable, all adjustments must be accomplished either before the garment is placed upon the form, 10 if it is to be adjusted to a definite size (and adjustment cannot be made readily to size after the garment is placed on the form), or else adjustment which is made externally is not to any given size, but merely to external flat measurements, 15 with the result that the sizing of the garment becomes largely a matter of guesswork. It is an object of this invention to provide a form upon which the garment may be placed, and thereafter the form may be adjusted to an exact size, the 20 indication of which and the control for which are readily accessible exteriorly of the form and of the garment thereon.

It is extremely advantageous to dry a dress after it has been properly stretched, or while it 25 is being stretched, and this is frequently accomplished by placing the garment upon a form which is pervious to air, steam or other fluids, and of a size and shape corresponding to the fictional "average figure", and then blowing such fluid 30 through the form while the garment is held thereon in distended fashion, but as noted above, such forms are not adjustable to precise size, or at all, nor in individual zones, and it is an object of the present invention to devise a form which is 35 adjustable in individual zones or with respect to the spacing of such zones, or both, and which is also of material which is pervious to the passage of such fluids, and which exposes substantially the entire area of the garment to the uniform 40 action of such fluids. This is especially desirable with velvet, for by so doing the pile may be caused to stand up uniformly, thereby avoiding flattened areas or "high lights".

It is a further object to provide such a form 45 having the capabilities and characteristics explained, which shall be of simple and comparatively inexpensive construction, durable, adapted to the various conditions and garments to be acted upon (for instance, of metal which cannot 50 absorb dyes nor be corroded by the fluids with which it may come in contact), and suitable to substantially universal use of cleaners.

With the above and other objects in mind, as will appear hereafter, my invention comprises 55 the novel form as a whole, and the novel parts thereof, and their combination and arrangement, as shown in the accompanying drawings, described in this specification, and as will be more particularly defined by the claims, which terminate the same.

In the accompanying drawings I have shown 60 my invention embodied in a representative form, it being understood that various changes may be made in the form, character and arrangement 65 of the parts, and in the individual parts themselves, without departing from the spirit of my invention.

Figure 1 is a general front elevation of the 70 form, parts being broken away to illustrate the interior mechanism, and Figure 2 is a general medial section along a plane from front to rear.

Figures 3, 4 and 5 are transverse sections, taken on the lines 3—3, 4—4 and 5—5, respectively, of Figure 1.

Figure 6 is an enlarged section of the control

and indicating mechanism, taken on a plane corresponding to that of Figure 2.

Figure 7 is a section taken on a plane corresponding to that of Figure 2, and as indicated at 7—7 of Figure 4, illustrating an expander device.

Figure 8 is an elevation of the control and indicating devices.

Figure 9 is a bottom plan view of certain guide elements used in conjunction with an expander. 10

Figure 10 is an enlarged elevation of details of the form itself, showing also certain arrangements for expanding the same.

Figure 11 is an elevation, and Figure 12 a section on the line 12—12 of Figure 11, showing a 15 separate form for attachment to the foundation form to obtain abnormal expansion at a given point.

The form as a whole is of the general shape of a human form. By this it is not meant to 20 imply that it is formed with a head, arms or separate legs, although the latter, for instance, might be used in sizing pants, such as ski pants, for instance. It is not meant to imply, either, that the figure must be of a shape to fit within 25 a complete dress, for it may be shaped only to receive only a skirt, or only to receive a jacket, and indeed it may be of a form to fit only within a sleeve, as for instance in resizing a knitted sleeve attached to a leather jacket. The figure, 30 therefore, may take various shapes, conforming in general to the human figure or to that part thereof which is to be sized, or conforming to the shape of the garment or part thereof which is to be resized. 35

Thus if it is to resize a puffed sleeve it may depart considerably from the shape of the human arm. Also it should be borne in mind that two or more such forms, as thus defined, may be combined in the sizing of a complete garment. A 40 sleeve form may be applied at the same time as the skirt and waist are being sized, or at a different time. The principles of the invention, however, will be described with reference to a figure which is of a shape to accommodate a complete 45 dress, from neck to hem, and it will be obvious how such principles can be applied to other forms or uses.

Such a figure, because it must be variable in size, and because it must be largely open for the 50 passage of drying or other operating fluids, is conveniently made up of a series of longitudinal strips 10 and cooperating circumferential strips 12 and 13, and special members such as 22, 32, 42, and 52, constituting an expandible and contractible basket-like figure. Preferably the longitudinal strips 10 are secured fixedly at the neck, as seen in Figure 6, and extend thence downwardly to a point below the hem, where they may be connected by springs 14 to a circumferentially 60 expandible hoop 6. By these or equivalent means the longitudinal members are tensioned, and yet are individually yieldable longitudinally as may be required by circumferential expansion at the different zones represented by the hoops 2, 3, 4, 65 5 and 6.

The function of the circumferential hoops 13 is to maintain approximately uniform spacing at the different levels between the longitudinal elements 10. They may be continuous or broken, 70 but if continuous, as is preferred, their ends are overlapped and are relatively movable, so that each one is circumferentially expandible and contractible, and each is movable somewhat with relation to the longitudinal strips 10. Such ex- 75

pansion and contraction of the hoops 13 would ordinarily be accomplished by the tendency of the longitudinal elements 10 to move outwardly when acted upon at the zones such as 4, 5 and 6, but means may be provided, if desired or found necessary, to positively expand and contract the hoops 13, for instance, in the manner now to be described relative to the other hoops.

The waist hoop 4 may be taken as typical in many respects of the hoops 2, 3, 5 and 6, and it is shown in detail in Figure 10. The discontinuous circumferential elements 12 and 42 are preferably connected together in overlapping relationship, as by means of the rivets 40 received in circumferentially disposed slots 41. They are of such slight thickness that this produces no appreciable break in the smooth surface of the dress. The members 42 constitute part of an expander. The expander hoops 42 being discontinuous, they may be contracted to the minimum waist measurement for which the figure is designed. These expander hoop elements 42 are simultaneously but differentially moved inwardly and outwardly by suitable means; for instance, they are carried upon the outer ends of links 43, pivoted to the expander hoops, which links, at their inner ends, are connected pivotally at points 44 to a rotatable element 45 in the nature of a cam or lever arm. It will be noted in Figure 4 that the expander element 42 at the front of the figure (at the waist) is carried upon a longer lever arm of the member 45 than the expander elements 42 at the two sides, and that the expander element 46 is not connected at all to the member 45, and therefore there is no rearward expansion. Rotation of the element 45 from the position shown in Figure 4 will cause the several links 43 to move inwardly toward the rod 7, which is the center of rotation of the member 45, the links 43 at each side moving by like amounts but considerably less than the distance through which the forwardly extending link 43 moves. As a result of such a differential arrangement the figure at the waist is expanded more greatly in a forward and rearward direction than it is expanded transversely, although there is some expansion transversely in keeping with the expansion forwardly and rearwardly. There is preferably, however, no expansion rearwardly, and the rear or small of the back may be taken as the initial point from which other measurements may be taken, in effect, if not actually.

The other hoops 2, 3, 5, and 6 are similarly expandible and contractible. The hip hoop 5 and the hem hoop 6 may be controlled identically and by the same means, for in this manner a skirt may be made to hang vertically from the hips, the expansion of the hem conforming in all respects to the expansion of the hips. It is not outside the scope of my invention, however, to provide independent means to expand the hem differently from or independently of the hip expander 5. I prefer that each of the hoops 2, 3, 4, and 5 be independently expandible and contractible. If an expander be employed at the shoulders, as indicated at 20, this may be controlled simultaneously with the neck expander at 2, but by different amounts and in a somewhat different manner. All necessary expansion at the shoulders can be achieved solely by transverse expansion.

The neck expander at 2 comprises the expander elements 22 to which the upper ends of the longitudinal members 10 are connected, upon which act the links 23 corresponding to the links 43,

connected at 24 to a rotative element 25. The circumferential hoop at the neck need not be continuous inasmuch as there is seldom any material at the neck which requires support except at the back of the neck.

Similarly at the bust the expanders 32 are suitably shaped, and are controlled by the links 33, connected at 34 to the rotative element 35. Here the rear element 36 is not expandible. In the bust hoop 3 the expansion is primarily forwardly and somewhat outwardly, this being controlled by the point of connection of each link 33 to the rotative element 35 and the relationship of such point of attachment inward towards or outward from the rod 7.

The hip hoop 5 is shown in Figure 5. Here the expanders 52 are operable by the links 53 connected at 54 to the rotative element 55. At this point the primary expansion is rearwardly, and the expansion transversely, while somewhat less than the expansion rearwardly, is still greater than the expansion forwardly, and this conforms in general to the contour of the human shape in this zone.

It will be recognized that all the expander elements 22, 32, 42, and 52 must be guided for expansion in a radial direction, and that they must be supported against sagging. To such end I provide suitable guides, indicated as the tubes 8, carried upon the rod 7 and projecting radially, in which are guided telescoping rods 80. The expander elements, as 42 (see Figure 7) are carried upon the outer ends of the rods 80, or in some cases (see Figure 9) are carried also upon the tubes 8. The tubes 8 adjacent the upright rod 7 are securely supported. Preferably, because it is desired to obtain vertical adjustment of the several zones, the guides 8 are not secured directly to the rod 7, but upon a collar 81 which is adjustable vertically along the rods, and which in turn is supported in a yoke 82 carried upon a substantial tube 84 which in effect forms the backbone of the figure, although it stands upright, not curved, and is suitably supported from a base or stand 85.

Such vertical adjustment may be accomplished by sliding the yoke 82 lengthwise of the backbone 84, and this adjustment carries with it the collar 81 and all associated parts. The expanders, such as 42, slide relative to the longitudinal members 10, the latter being slotted, as indicated at 17, whereby certain rivets 15, received in such slots to hold the longitudinal members 10 and circumferential members 12 together and to space apart the longitudinal members, may slide vertically (see Figure 10). The yoke 82 is held in adjusted position lengthwise of the backbone 84, which preferably is graduated in inches, by convenient means such as the set screw 87. Thus each adjustment of a zone vertically, that is, each adjustment of the spacing of adjacent zones, is individually accomplished, but this can readily be done before the garment is put in place upon the form, and is done in conformity with measurements of the person whom the dress is to fit, which the cleaner will previously have obtained.

The rotation of the elements 25, 35, 45, and 55 is preferably accomplished from a point externally of the form and of the garment supported thereon, so that it may be accomplished after the garment has been put in place upon the figure. To this end I provide a series of tubes 70 and 71 fitting about the rod 7 and ex-

tending downwardly from a point above the neck of the figure, to engage one or more of the collars 81, in such a manner that when any given tube or the rod 7 is rotated it will effect the rotation of the connected collar 81, and thereby effect rotation of the corresponding element, as 45, and the expansion of the corresponding expanders, as 42. Thus by providing a key way in each of the collars 81, and a key 79 upon the tubes, the collar is rendered capable of considerable vertical adjustment, within such limits as may be necessary, without affecting the rotative connection between the tube and the collar.

Rotation is conveniently accomplished by providing at the neck a series of rotatable handles or disks 72, 73, 74, and 75. The member 72 may be formed integral with the rotative member 25 which controls the expansion of the neck. The member 73 is connected to the tube 71 which controls expansion of the bust zone at 3. The rotatable control member 74 is connected to the tube 70 which effects expansion of the waist zone at 4, and the control element 75 is connected to the rod 7 which controls expansion at the hip zone 5 and at the hem 6. The whole is supported in a yoke 76 fixed upon the upper end of the backbone 84, the edge of which, as is shown in Figure 8, cooperates with size indicia placed upon the respective control elements. To prevent the stiffness of the form elements 10 and 13 from reversely rotating the control members each one may be held in an adjusted position by suitable means such as the set screws 77.

It will now be apparent that in the use of the form the several expanders are adjustable longitudinally of the figure to achieve the proper spacing between these zones. The waist expander 4 may be fixed in position, if desired, and the other expanders adjusted longitudinally with respect to the expander 4, or all may be adjustable. The proper spacing having been achieved, the figure would normally be contracted circumferentially to a size somewhat less than the final size of the garment, which has probably been shrunk to a smaller size than it was originally, and the garment is put in place upon the figure. From measurements previously obtained the several control and operating members 72, 73, 74, and 75 are set to the proper sizes, expanding the figure and the garment upon it, the latter uniformly and radially throughout its area. Because the several expansion zones have been properly adjusted longitudinally, the bulge at the hips or at the bust occurs at the proper point in the garment. Because the sizes circumferentially have been accurately determined and are accurately set, the garment is expanded to just the proper degree—no more and no less. Should a particular individual be of excess size in any particular, separable forms, such as the bust forms 9, shown in Figures 11 and 12, and composed of basket-like elements, may be hung upon the main form at proper locations, hooks 90 being provided for such a purpose. Such a form is indicated in place in the dotted lines of Figure 2. Such forms may be provided in sufficient variety and shape to accommodate any desired expansion at particular points, but would only be required for abnormal human shapes.

With the garment now secured on the figure, the hem line is straightened, and its length measured from the waist, for example, and it is held in place, thus straightened, by any suitable means. To this end I may employ a flexible tape 91, provided with a multiplicity of points which will

project into but not injure the material of the garment, and which may be wrapped around the garment and the figure at the hem line, with its ends pinned or otherwise suitably held in place. This will hold the hem even and at the proper distance below the waist. A similar tape may be employed at other points, as the waist.

Now if the garment is to be dried, a blower B, suitably driven, is supported with its nozzle N directed upwardly beneath the bottom of the figure and into the interior of the garment held thereon. By these or other suitable means a fluid, such as warm air, or steam, is supplied to the interior of the garment, and because the form is entirely of openwork, basket-like in character, and of slight aggregate area, the entire garment is subjected substantially uniformly to the action of such fluids. The garment may be subjected to various operations while thus held on the form at the proper size. After drying, a sizing substance may be supplied to it, to assist in holding its shape. After these operations are completed the figure may be collapsed and the garment removed therefrom. Because the form is adjustable, both as to spacing of the zones of measurement and as to the circumferential measurements in each zone, and because it can be adjusted to the measurements of any given individual, which will be obtained by the cleaner in advance, it follows that the garment, when completed, must be exactly shaped and sized to the particular individual. Because the stretching is uniform throughout its area there is little likelihood that the material of the garment will be stretched unduly or injured in any way.

What I claim as my invention is:

1. A cleaner's garment sizing form comprising a figure formed with flexible longitudinal strips and flexible, extensible circumferential strips interengaged therewith, the whole being generally of human shape, the circumferential strips being adjustable longitudinally of the form, and means to expand and contract said circumferential strips in any position of their adjustment simultaneously in substantially all directions, but by different amounts in different directions.

2. A cleaner's garment sizing form comprising a figure shaped generally to the parts of the human body which are clothed by such garment, means to expand said figure circumferentially and simultaneously in substantially all directions, but by different amounts in different directions, in a selected zone or zones, such as the waist, bust, and hips, and means to vary the spacing, lengthwise of the figure, of one such zone from another.

3. A cleaner's garment sizing form comprising a reticulated figure shaped generally to resemble a human shape, means to expand said figure circumferentially and simultaneously in substantially all directions, but by different amounts in different directions in selected spaced zones, and means to adjust one or more of such expanding means lengthwise of the figure, to vary the spacing of the expandible zones.

4. A cleaner's garment sizing form comprising an upright support, an enclosing figure generally of human shape and variable in size, carried by said support, a plurality of means adjustable lengthwise of said support, engageable with the figure at zones of size variation, as the bust, waist, or hips, and by such adjustment varying the spacing of such zones, said means being each simultaneously expandible in substantially all directions, but by different amounts in different

directions in any position of adjustment, to vary the radial amount of the expansion in given directions, and the circumferential measurement of the figure, in the corresponding zone.

5. A cleaner's garment sizing form comprising an upright support, an enclosing figure generally of human shape and variable in size, carried by said support, a plurality of means adjustable lengthwise of said support, engageable with the figure at zones of size variation, as the bust, waist, or hips, and by such adjustment varying the spacing of such zones, and means disposed externally of the form, and operatively engaged with the first means in all adjusted positions of the latter, to expand such first means, each independently and simultaneously in substantially all directions, but by different amounts in different horizontal directions, to vary the circumferential measurement of the figure in selected zones, and the amount of its expansion in each direction.

6. A cleaner's garment sizing form comprising an upright support, an enclosing figure generally of human shape and variable in size, carried by said support, a plurality of expanders disposed within the figure at zones of size variation, as the bust, waist, or hips, and each including a ro-

tative member, a plurality of rotative indicating and control means carried by said support, adjacent the neck of the figure, a plurality of concentric tubes, each one connecting a control means with the rotative member of the corresponding expander, whereby rotation of a control means rotates the connected rotative member of the corresponding expander, to vary the measurement at its zone, in correspondence with the indicator, and means whereby each expander and its rotative member may be adjusted lengthwise of its tube, to vary the spacing of selected zones.

7. A cleaner's garment sizing form comprising a figure generally of human shape and variable in size, a rotative cam within the figure, disposed in the general plane of a zone of circumferential expansion, links radiating from and operatively connected at their inner ends to said cam, and operatively connected at their outer ends to different portions of the figure at points angularly spaced about the zone of expansion, the connection between the cam and said links being formed and arranged to accomplish expansion of the form in different degrees at the different points of connection of the links.

WALLMUTH R. FRENTZEL.
